(57) **CLAIM**

The ornamental design for a riding helmet, as shown and described.

DESCRIPTION

FIG. 1 is a front perspective view of a riding helmet, showing our new design;

FIG. 2 is a front view thereof;

FIG. 3 is a left side view, with the right side view being a substantial mirror image thereof;

FIG. 4 is a top view thereof; and,

FIG. 5 is a rear view thereof.

Any broken line depictions illustrate environmental structure and form no part of the claimed design.

1 Claim, 5 Drawing Sheets
